UNITED STATES PATENT OFFICE.

JOHN L. McMILLAN, OF SYRACUSE, NEW YORK.

LOOSE-LEAF BINDER.

1,106,825.

Specification of Letters Patent. Patented Aug. 11, 1914.

Application filed November 9, 1910. Serial No. 591,442.

To all whom it may concern:

Be it known that I, JOHN L. McMILLAN, a citizen of the United States, residing at Syracuse, in the county of Onondaga and State of New York, have invented certain new and useful Improvements in Loose-Leaf Binders, of which the following is a specification.

My present invention pertains to improvements in loose-leaf binders, the same being an improvement upon the construction set forth and claimed in Letters Patent granted to Sydney C. Nott, No. 816,734, dated April 3, 1906.

The main object of the present invention is to improve and simplify the construction set forth in the patent just mentioned and to produce a stronger and somewhat more durable binder than is described in the patent referred to.

A further object of the invention is to provide means for automatically locking the levers which work in conjunction with the binding posts when said levers are depressed, and the leaves of the book are placed under compression.

A still further object of the invention is to provide means for preventing rotation of the binding posts and the reversely-hinged levers when the levers and binding posts are brought into alinement, with the view of unclamping the leaves for the insertion or withdrawal thereof, thus preventing any swinging movement of the levers upon their hinged connection with the binding posts, which movement would result in the presentation of projections at the hinge joints and the consequent danger of mutilation of the leaves.

With these and other objects in view, the invention will be set forth, reference being had to the annexed drawings; wherein:

Figure 1 is a perspective view of the loose-leaf binder, parts being broken away to more clearly illustrate the invention; Fig. 2 is a longitudinal vertical sectional view, taken through the midlength of the binding and clamping plates; Fig. 3 a top plan view of a portion of the clamping plate and the related parts; Fig. 4 a transverse vertical sectional view taken on the line 4-4 of Fig. 2; Fig. 5 a similar view taken on the line 5-5 of Fig. 2; Fig. 6 a longitudinal sectional view, similar to Fig. 2, of one end of the clamping and binding plates, the clamping

lever being shown as thrown up into alinement with the binding post and the binding plate and clamping member being shown as separated to their full extent; Fig. 7 a perspective view of one of the clamping levers, 60 the sectional post and the binding bolt or screw; Fig. 8 a horizontal sectional view taken on the line 8-8 of Fig. 6; Fig. 9 a similar view taken on the line 9-9 of Fig. 6; Fig. 10 a perspective view of one of the 65 spring latches which coöperate with the clamping lever; and Fig. 11 a fragmentary view of a portion of one form of leaf which may be used with the binder; Fig. 12 a side elevation of a modified form of clamping 70 lever; and Fig. 13 a plan view of a portion of the clamping plate, showing the form of opening which coöperates with said modified form of lever.

Referring to said drawings, 1 denotes the 75 binding plate, the main body of which is preferably formed of wood and has secured to its upper or inner face a metallic plate 2. Riveted to the metallic plate 2 and lying between said plate and the member 1 are two 80 hinge members 3 (see Fig. 5). Said hinge members are adapted to coact with a metallic plate or bar 4 (see Figs. 4 and 9), the outer edge of which is secured to the hinge members 3 by a pintle or rod 5. The other 85 edge of the plate is seated in the back or cover-board 6 of the book, which cover-board and plate will preferably be covered with suitable material, such as leather, buckram or the like.

A clamping plate, designated as a whole by 7, is formed of a piece of metal, preferably steel, the inner or effective clamping portion 8 of which is of substantially the same width as the binding plate 2, and from the outer or back edge of said member 8 there extends upwardly a section or wall 9, and from this projects forwardly and over the plate 8 a ledge or lip 10, the member thus formed being in effect a channel-bar 100 having one short side. Said bar forms a housing for the locking or clamping levers and the supports for the combined hinge members and supports for the latches which coöperate with the levers.

Secured to the upper face of the member 8, adjacent to each end thereof, is a cast block or member 11, the forward end of which projects beyond the edge of the member 8 and is provided with an opening for 110

the reception of a hinge rod or bar 12. Said rod or bar passes through the barrel formed upon the metal plate 13, which plate is secured in the inner edge of the front cover-board.

5 The binding member has an opening formed therein adjacent to each end, the outer portion of each opening being larger than the inner portion, to receive the head 10 of the screw 16. Openings are likewise provided in the clamping member 8 in line with the openings in the binding member, and binding-posts are adapted to be passed through said openings. Each post 15 comprises a screw member 16, just referred to, and a series of threaded sections 17 (one or more), and likewise a section 18. As will be clearly seen upon reference to Figs. 2, 6 and 7, the screw or bolt 16 is adapted to be inserted in the lower internally-threaded end 20 of the section 17, while the upper reduced and threaded end of said section 17 is adapted to be secured in the lower internally-threaded end of the member 18. The sections 25 17 will in practice be made of different lengths, as will also the screws, in order to produce posts adjustable as to length. Said posts may also be varied in length by screwing a bolt 16 in a section 17 to a greater or 30 less extent. So, too, the post may be lengthened or shortened by varying the amount of engagement between the threaded members upon the section 17 and the member 18, or between any of the sections, though it is 35 preferable to have the sections screwed tightly together. To enable one to readily screw the sections together tightly or to separate them when occasion demands, the sections are provided with holes or openings 40 17^a, through which a tempered wire may be inserted to afford proper purchase or leverage to enable one to screw or unscrew the sections, as the case may be.

The upper end of the member 18 is angled 45 and bifurcated, and into the bifurcated end there extends a tongue or member 19 formed upon the lower end of the clamping member 20. Said clamping member or lever is likewise provided with angled faces complementary to the angled faces formed upon the 50 upper end of the member 18, so that when the parts are brought into alinement they will be prevented from being moved beyond that point. In other words, the connection 55 is a lock hinge, which while permitting the parts to swing in one direction prevents them from passing beyond a certain point in another direction. The tongue or member 19 is of a width less than the diameter of the section 18, and a channel or groove 21 is formed in the side of the lever 20, extending longitudinally thereof and in line with the reduced side of the tongue 19. A stop 22 is provided at the outer end of the groove or 60 channel 21, the purpose of which will here-

inafter appear. One face of the tongue 19, or that which lies in alinement with the groove 21, is rounded (see Fig. 2), while the opposite face is cut away to form a locking shoulder or projection 23. Said shoulder 70 coacts, when the levers are in locking position, with a latch, which latch serves to hold the levers in their depressed position. There is a latch for each lever, and each latch may be said to comprise an L-shaped plate 24, provided at its outer free end with a tongue or projection 25 adapted to coact with the groove 21 when the lever is thrown upwardly into its vertical position (see Fig. 8), the plate being secured to one end of a plunger 26, mounted and working in a recess 75 formed in the block or casting 11. The plunger is provided with a stem 27 about which is encircled a spring 28, said spring tending to force the plunger outwardly toward the locking post and consequently throw the latch into operative relation with the lever, whether it be in its clamping position or thrown into its upright position, as 80 in Figs. 6 and 8.

90 In order to provide a fulcrum for the lever, a bearing plate 30 is secured upon the member 8, said plate extending beneath the casting or block 11, and being secured in position by the same rivets as are employed 95 to secure said block 11 in place. As will be seen upon reference to Figs. 2, 3, 6 and 8, said bearing plate extends a short distance beyond the opening formed in the clamping member through which the post extends; 100 consequently, when the lever is thrown downwardly it will contact with said plate adjacent to the opening and the plate will form a fulcrum therefor, which enables one to exert considerable pressure upon the 105 leaves, drawing the binding and clamping plates tightly together. While the employment of this plate is preferred, as it enables one to readily procure the necessary compression and affords a stronger structure, its 110 presence is not necessary. As before stated, when the lever has been forced downward to its full extend, the latch will automatically move outwardly and lock the same in its adjusted position. It will be understood that 115 the length of the post may be varied by adjustment of the parts, screwing them together or apart to a greater or less extent, or by the substitution of longer or shorter sections 17, or longer or shorter screws.

120 In the commercial form of the book, the various parts will be covered with leather or the like, and such material is shown in section in several of the figures and is designated throughout by 29. In other words, 125 those metallic parts which would come in contact with the desk when the book is being used, will be covered so as to prevent injury to the desk.

130 In use (assuming that a notched leaf as

shown in Fig. 11 is employed) the levers will be thrown into their upright or vertical position, as indicated in Fig. 6, at which time the tongues or projections 25 upon the 5 latches extend into the grooves or channels 21, thus holding the levers and posts against rotation and consequent possible elongation or shortening by a screwing or unscrewing of the parts. Furthermore, by reason of the 10 fact that when properly positioned the levers swing toward each other, and the further fact that the hinge stop or lock joints then work in opposition to each other, and that the levers are in effect connected by the 15 clamping plate, when said plate is elevated, there can be no swinging movement of the levers relatively to the posts. Consequently, the hinge connection between the levers and the sections 18 of the posts will be smooth, 20 there being no projections or protuberances which would catch the leaves and tear them. As will likewise be seen upon reference to Fig. 6, the stops 22 act to prevent the clamping plate from being moved off of the levers 25 20, such stops coacting with the tongues 25 of the latches. When the necessary number of leaves has been inserted, the clamping plate or member is moved downwardly and the levers swung over into the position shown 30 in Fig. 2, the curved face of the tongue or projection 19 riding beneath the plate 24, or more specifically beneath the tongue 25, and forcing the latch rearwardly until the lever has been thrown downwardly to such 35 an extent that the latch may be again moved forward and pass beneath the shoulder or reduced portion 23. Where the leaves have merely the perforations, without the slots or openings extending from the edges to said 40 perforations, then the clamping plate with the cover-board 14 will be removed and the leaves slipped over the then upright levers and the binding posts to which said levers are connected. Such leaves will be re- 45 moved in a reverse manner. Reverting to the levers and the coacting latches, or more specifically the tongues 25 of such latches, it will be noted that when the levers are drawn upwardly into their vertical position they 50 are prevented from turning and consequently they are always in a position where they may be thrown downwardly into the channel member or housing. Furthermore, by reason of the fact that they cannot be 55 rotated while thus locked, they cannot be shortened or lengthened by sections screwing on or off of each other, or the post as a whole screwing on or off of the screw or bolt 16. 60 Figs. 12 and 13 show another form of lever and clamping-plate. The lever 20^a is provided with a flat face 21^a and a stop 22^a at its upper end. A clamping-plate 7^a is formed with openings, each having a 65 straight face 7^b, coacting with face 21^a and

preventing rotation of the lever when the lever is elevated and the plate raised. The upper end of the post 18^a is flattened as at 18^b, forming a continuation of face 21^a. This permits the upper end 18^b to be drawn 70 through plate 7^a when the parts are brought to position, as in Fig. 2. As will be seen, the contour of the opening in plate 7^a is substantially the same as the cross-section of the lever, but inasmuch as the lever is provided with a stop finger 19^a, to prevent it swinging past the vertical when thrown upwardly, it is necessary to form a notch 19^b to permit 75 said finger to pass outwardly when the plate 7^a is lowered and the lever 21^a is swung 80 downwardly into clamping position. Said notch is also necessary when an opposite movement of the lever is effected. The stop finger may also act with a latch, as in the construction above set forth. Stop 22^a prevents 85 the clamping plate from being drawn off of the end of the lever when the parts occupy the position shown in Fig. 6.

Having thus described my invention, what I claim is:

1. In a binder, a binding-post comprising one or more sections adapted to be engaged with a binding plate and to extend through a clamping plate; a lever hinged to the upper end of the post; and an automatic lock 90 to engage the lever when it is forced into its clamping position.

2. In a binder, the combination of a binding plate; a clamping plate; posts connected to the binding plate and extending 95 through the clamping plate; a lever connected to the upper end of each post, said lever forming, when extended, a continuation of its post; and an automatic retaining device 100 for engaging each lever when the lever is 105 thrown down into clamping position.

3. In a binder, the combination of a binding plate or member; a plurality of posts extending upwardly therefrom; a metallic clamping plate, said plate having in cross-section the form of a channel bar with one short side, the inner or long side thereof being provided with openings through which the posts may pass; and a clamping lever pivotally connected to the upper end of each 110 post, said levers, when thrown down into clamping position, being housed by the clamping plate.

4. In a binder, the combination of a binding plate or member; a plurality of posts adjustable as to length extending upwardly therefrom; a metallic clamping plate, said plate having in cross-section the form of a channel-bar with one short side, the inner or long side thereof being provided with 120 openings through which the posts may pass; and a clamping lever pivotally connected to the upper end of each post, said levers, when thrown down into clamping position, being housed by the clamping plate.

5. In a binder, the combination of a binding plate or member; a plurality of posts extending upwardly therefrom; a metallic clamping plate, said plate having in cross-section the form of a channel-bar with one short side, the inner or long side thereof being provided with openings through which the posts may pass; a clamping lever pivotally connected to the upper end of each post, said levers, when thrown down into clamping position, being housed by the clamping plate; and means carried by the clamping plate for retaining the levers in their depressed position.
- 15 6. In a binder, the combination of a binding member; a plurality of extensible posts extending upwardly therefrom; a clamping member provided with openings through which the posts may extend; a lever pivoted to the upper end of each post; and means carried by the clamping member for holding the levers in their depressed clamping position and for preventing axial movement of said levers when raised into alignment with the posts.
- 20 7. In a binder, the combination of a binding member; a plurality of longitudinally-adjustable posts extending upwardly therefrom; a clamping member provided with openings through which the posts may extend; a lever pivoted to the upper end of each post; and means carried by the clamping member for holding the levers in their depressed clamping position and for preventing rotation of said levers when raised into alignment with the posts.
- 25 8. In a binder, the combination of a binding member; a plurality of posts adjustable as to length extending upwardly therefrom; a clamping member provided with a series of openings through which the posts may pass; a clamping lever pivoted in the upper end of each post, each lever having a groove extending lengthwise thereof in its face; and a member adapted to enter said groove when the lever is thrown into its upright position and to thereby prevent rotation of the lever about its axis.
- 30 9. In a binder, the combination of a binding member; a series of posts adjustable as to length extending upwardly therefrom; a clamping member provided with a series of openings through which the posts may pass; a clamping lever mounted upon the upper end of each post; and means for holding the levers against axial rotation when the same are thrown upwardly into alignment with the posts.
- 35 10. In a loose-leaf binder, the combination of a binder member; a clamping member; a plurality of posts extending from the binder member through the clamping member; a clamping lever hinged to the upper end of each post; and means for holding each lever in alignment with its post

when the levers are turned upwardly, permitting a movement of the clamping member away from the binder member.

11. In a loose-leaf binder, the combination of a binder member; a plurality of posts extending upwardly therefrom; a clamping member provided with openings corresponding in number and position to the posts; a bifurcated member secured to the upper end of each post; a lever having a tongue of a width less than the width of the slot in said bifurcated member and extending into the same, said lever having also a groove extending lengthwise thereof in line with the tongue; a hinge-pin connecting the tongue and bifurcated member; and a latch having a tongue adapted to cooperate with the groove to hold the post and lever against rotation.

12. In a binder, the combination of a binding-plate; a clamping-plate; an extensible binding-post comprising one or more sections extending from the binding-plate and through the clamping-plate; a lever hinged to the upper end of the post; and an automatic lock carried by the clamping-plate and engaging the lever when it is in its upright position in line with the post to hold the same against rotation.

13. In a binder, the combination of a binding-plate; a clamping-plate; an extensible binding-post comprising one or more sections projecting from the binding-plate and extending through the clamping-plate; a lever hinged to the upper end of the post; and an automatic lock carried by the clamping-plate to engage the lever, said lock holding the lever, when it is turned down into its clamping position, and normally maintaining it in such position, and likewise engaging the lever when it is turned upwardly into alignment with the post to hold said lever and post against rotation.

14. In a binder, the combination of a binding-plate; a clamping-plate; an adjustable binding-post comprising one or more sections engaging the binding-plate and extending through the clamping-plate; a lever hinged to the upper end of the post, said lever being provided with a groove extending longitudinally of the face thereof; and a latch carried by the clamping-plate adapted to engage one end of the lever when it is thrown downwardly into clamping position, and to enter the groove when the lever is thrown into its upright position in axial alignment with the post.

15. In a binder, the combination of a binding-plate; a clamping-plate; an adjustable binding-post comprising one or more sections engaging the binding-plate and extending through the clamping-plate, the upper end of the post being bifurcated; a lever pivoted to the post and having a tongue adapted to extend into the opening formed

in the top of the post, said lever being likewise provided with a groove extending longitudinally of the outer face thereof in line with the tongue; and a latch mounted upon 5 the clamping-plate, adapted to engage the tongue on the end of the lever when the lever is thrown downwardly into its clamping position and to enter the groove when the lever is thrown upwardly into axial alinement with the post.

16. In a binder, the combination of a binding plate; a clamping plate; a pair of posts extending from the binding plate up through openings formed in the clamping 15 plate; a lever hinged to the upper end of each post, the hinges being of such construction as to prevent the levers from being thrown beyond the vertical when swung in one direction; and means carried by the 20 clamping plate for engaging said levers when they are thrown upwardly into axial alinement with the posts, and preventing the same from rotating.

17. In a binder, the combination of a binding plate; a plurality of posts extending upwardly therefrom; a clamping plate provided with openings through which said posts may extend; a lever pivotally connected to the upper end of each post; and means 30 carried by the clamping plate and engaging the levers, when they are thrown out of their clamping position into alinement with the posts, for preventing the clamping plate from being withdrawn over and off of the 35 ends of the levers.

18. In a binder, the combination of a binding plate; a plurality of posts extending upwardly therefrom; a clamping plate provided with openings through which said 40 posts may extend; a lever pivotally connected to the upper end of each post; spring-pressed latches engaging said levers, when they are thrown out of their clamping position into alinement with the posts, for preventing the clamping plate from being withdrawn over and off of the ends of the levers.

19. In a binder, the combination of a binding plate; a plurality of posts extending upwardly therefrom; a clamping plate having 50 openings formed therein through which said posts may extend; a lever hinged to the upper end of each post, the hinge connection being such that as the levers are brought into axial alinement with the posts they are arrested against further movement, each lever having a groove or channel extending longitudinally thereof; a shouldered projection formed upon the lower end of each lever adjacent to the hinge connection; a stop provided at the outer end of the groove in each lever; and a spring-pressed latch for each lever carried by the clamping plate, said latch being provided with a tongue adapted to enter the groove in the adjacent lever 55 when said lever is thrown upwardly, the

latch, when the lever is thrown downwardly into clamping position, engaging the shouldered projection.

20. In a binder, the combination of a binding plate; a plurality of posts extending upwardly therefrom; a clamping plate having a series of openings formed therein through which said posts may pass; a clamping lever hinged to the upper end of each post, said lever being provided with a groove or channel extending longitudinally thereof, in its outer face; a shouldered projection formed upon the end of the lever adjacent to the hinge connection; a block or casting secured to the clamping plate adjacent to each of the openings formed therein; a spring-pressed latch mounted in said casting, said latch being provided with a tongue adapted to extend into the groove aforesaid when the lever is thrown upwardly into alinement with the post; and a stop carried by each of the levers at the outer end of the groove or channel, adapted to coact with said tongue to prevent complete separation of the clamping plate from the lever except when said latch is manually retracted.

21. In a binder, the combination of a binding plate; a clamping plate; a plurality of posts extending from the binding plate through openings formed in the clamping 95 plate, said posts being adjustable as to length; a lever for each post; a stop hinge connection between the upper end of each post and its lever, each lever being likewise provided with a groove or channel extending lengthwise thereof in its outer face; and a spring latch carried by the clamping plate adjacent to each of the posts, said latch being provided with a tongue adapted to enter the groove in the adjacent lever when said lever is thrown upwardly, preventing rotation thereof, and to engage the inner or lower end of the lever when the lever is thrown downwardly into clamping position.

22. In a binder, the combination of a binding member; a series of extensibly adjustable posts extending upwardly therefrom; a clamping member provided with a series of openings through which the posts may pass; a clamping lever mounted upon the upper end of each post; means carried by the levers; and means carried by the clamping member, said means coacting with each other to prevent axial rotation of the levers when the same are thrown upwardly into alinement with the posts.

23. In a binder, the combination of a binding-plate; a clamping-plate; an extensible binding-post, comprising one or more sections, extending from the binding-plate and through the clamping-plate; a lever hinged to the upper end of the post; and a lock carried by the clamping-plate and engaging the lever when it is in its upright position in line with the post to hold the same against rota- 125

tion and likewise to engage said lever to hold it in its depressed or clamping position.

24. In a binder, the combination of a binding plate; a clamping plate; a pair of posts extending from the binding plate through openings formed in the clamping plate; a lever hinged to the outer end of each post, said levers normally swinging toward each other and the hinges being so formed as to prevent the levers from being thrown beyond the vertical when the levers are swung upwardly; and means carried by the clamping

plate engaging said levers when they are thrown upwardly into axial alinement with the posts for preventing rotation of said levers and consequent displacement of the parts.

In testimony whereof, I have signed my name to this specification in the presence of two subscribing witnesses.

JOHN L. McMILLAN.
